G. W. PROBST.
RAIL JOINT.
APPLICATION FILED NOV. 22, 1919.

1,335,751.

Patented Apr. 6, 1920.

UNITED STATES PATENT OFFICE.

GEORGE WASHINGTON PROBST, OF LOCK HAVEN, PENNSYLVANIA, ASSIGNOR OF ONE-
THIRD TO RAY S. PROBST AND ONE-THIRD TO VERNE PROBST, BOTH OF LOCK HAVEN,
PENNSYLVANIA.

RAIL-JOINT.

1,335,751.

Specification of Letters Patent.

Patented Apr. 6, 1920.

Application filed November 22, 1919. Serial No. 339,784.

To all whom it may concern:

Be it known that I, GEORGE W. PROBST, a citizen of the United States, residing at Lock Haven, in the county of Clinton and State of Pennsylvania, have invented a new and useful Rail-Joint, of which the following is a specification.

The device forming the subject matter of this application is a rail joint, and the invention aims to provide a joint which will 10 not be depressed by passing traffic. Another object of the invention is so to construct the joint that there will be no pronounced shoulder producing, in common and known constructions, a pounding action 15 when the rolling stock passes the joint.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention.

30 In the accompanying drawings:—

Figure 1 shows in top plan, a device constructed in accordance with the invention, parts being broken away; Fig. 2 is a longitudinal section, parts being broken away; 35 Fig. 3 is a cross section on the line 3—3 of Fig. 1; Fig. 4 is a cross section on the line 4—4 of Fig. 2; Fig. 5 is a side elevation wherein parts are broken away; and Fig. 6 is a composite perspective showing certain co-operating parts of the device, the view being diagrammatic to some extent.

The device forming the subject matter of this application comprises a pair of rails having reduced overlapped parts 1 defining transverse shoulders 2, the end of said part of one rail co-operating with the shoulder 2 of the other rail. The parts 1 are provided in their inner surfaces with longitudinal 45 grooves 3 communicating with transverse seats 4 formed in the shoulders 2, each part 1 having a terminal notch 5 complementary to the seat 4 in the shoulder 2 of the other

5 rail. A key 6 is located in the grooves 3 and is provided with oppositely extended projections 7 received in the seats 4 and in the notches 5.

The co-operating ends of the rails may be received in chairs 8, the chairs, the members 1 and the intermediate portion of the key 6 being provided with elongated openings 9 adapted to receive bolts 10 or other securing devices.

Each rail, preferably, includes, as usual, a ball 11, a web 12 and a flange 14. At the 65 ends of the rails, the flange is thickened, as shown at 15 so that the grooves 3 may be fashioned readily therein without weakening the rails to any appreciable extent. If desired, the chairs 8 may be connected with 70 the thickened portions 15 of the webs 12 by means of bolts 16 mounted in elongated openings 17 fashioned in the chairs 8 and in the thickened portions 15 of the rails.

It will be obvious from the foregoing that 75 the parts 1 of the rails are overlapped in such a manner, that before the wheel passes from one rail, the wheel will be received on the other rail. A pounding at the joints, therefore will be avoided. Further, owing 80 to the way in which the key 6 connects the ends of the rails, the rails will not be depressed readily, and low joints will be avoided.

Having thus described the invention, what 85 is claimed is:—

1. A pair of rails having reduced overlapped parts defining transverse shoulders, the end of said part of one rail co-operating with the shoulder of the other rail, said 90 parts having longitudinal grooves at their inner surfaces communicating with transverse seats formed in the shoulders, each part having a terminal notch complementary to the seat in the shoulder of the other rail; 95 a key in the grooves and provided with oppositely extended projections received in the seats and in the notches; and means for retaining the rails against lateral separation.

2. A pair of rails each including a ball, a 100 web and a flange, the rails having reduced overlapped parts defining transverse shoulders, the end of said part of one rail co-operating with the shoulder of the other rail, said parts having longitudinal grooves 105 in their inner surfaces communicating with

transverse seats formed in the shoulders, each part having a terminal notch complementary to the seat in the shoulder of the other rail; a key in the grooves, the webs being thickened at the ends of the rails to facilitate the formation of the grooves, the key being provided with oppositely extended projections received in the seats and in the notches; and means for retaining the rails against lateral separation.

3. A pair of rails having reduced overlapped parts defining transverse shoulders, the end of said part of one rail coöoperating with the shoulder of the other rail, said parts having longitudinal grooves in their inner surfaces communicating with trans-

verse seats formed in the shoulders, each part having a terminal notch complementary to the seat in the shoulder of the other rail; a key in the grooves and provided with oppositely extended projections received in the seats and in the notches; fish plates coöperating with the ends of the rails; and securing elements passing through the fish plates, said parts and the key.

In testimony that I claim the foregoing as my own, I have hereto affixed my signature in the presence of two witnesses.

GEORGE WASHINGTON PROBST.

Witnesses:

ROY S. PROBST,
ISAAC RUMBERGER.
